Inventor:
Alfred C. Finney,
by Albert G. Davis
His Attorney.

UNITED STATES PATENT OFFICE.

ALFRED C. FINNEY, OF SCHENECTADY, NEW YORK, ASSIGNOR TO GENERAL ELECTRIC COMPANY, A CORPORATION OF NEW YORK.

GROUND DETECTOR.

Application filed April 20, 1921. Serial No. 462,819.

To all whom it may concern:

Be it known that I, ALFRED C. FINNEY, a citizen of the United States, residing at Schenectady, in the county of Schenectady,

5 State of New York, have invented certain new and useful Improvements in Ground Detectors, of which the following is a specification.

My invention relates to ground detectors 10 and has for its object to provide means operative continuously for detecting and indicating the location and character of grounds on an electric system without interfering with the otherwise normal operation of the system.

In the operation of rolling mills in steel plants, considerable water is usually present as leakage from hydraulic control apparatus and also as waste from the water used to 20 cool the rolls. Conditions are, therefore, very favorable for grounds and with the great amount of metal, that is to say good conducting material, present, it becomes highly desirable at all time to know in- 25 stantly without interrupting the rolling operation whether a ground is present and, if so, its location and character, otherwise operation may be continued under conditions dangerous not only to the apparatus

30 but also to the operators. Other dangerous conditions, especially in shape mills, arise when a piece of steel in the rolls gets temporarily out of control as in the case of "cobbles". Before the mill can be stopped, 35 the piece forming the "cobble" is apt to twist and squirm in all directions with the possibility of striking live conductors or other electrical apparatus used in driving the mill and thereby causing grounds.

40 My invention is particularly applicable for the detection of grounds on electrically driven rolling mill systems, although its application is not limited to this relation of utility.

45 My invention will be better understood from the following description taken in connection with the accompanying drawing, and its scope will be pointed out in the appended claims.

50 Fig. 1 illustrates diagrammatically an embodiment of my invention; Fig. 2 illus-

trates diagrammatically a modification of my invention; and Fig. 3 illustrates diagrammatically another modification of my invention.

55 In Fig. 1, there is shown a fly-wheel motor-generator set arranged to supply the motors of a rolling mill or other load apparatus. The arrangement shown comprises an alternating current circuit 1 supplying a motor 2 which is preferably direct-connected to a plurality of direct current generators 3 by a shaft 4 on which is mounted a fly-wheel 5. The generators 3 are shown arranged alternately in a series circuit with a plurality of motors 6 which drive a rolling mill or other machinery 7.

60 In order to have a continuous indication as to the presence of grounds, the location and character thereof if any occur on this 70 system, I provide in a circuit 8 across one of the dynamo-electric machines, for instance in the form of my invention shown in Fig. 1, one of the motors 6, a control means or electro-responsive device 9. The form of 75 control means I prefer to use is of a type known in the art as a differential relay and in the example shown comprises two windings 10 and 11 arranged in series with the circuit 8 to control the movement of contact controlling members 12 and 13.

80 The circuit 8 is grounded at a point 14 intermediate the windings 10 and 11. The windings 10 and 11 operate with a differential action to move the contact controlling members 12 and 13 by armatures 15 and 16 pivotally related to a lever 17 which is fulcrumed at a point 18 and carries the contact controlling members 12 and 13. The contact controlling members 12 and 13 are 85 arranged to bridge contacts 19 and 20 respectively and thereby to control circuits including signaling means 21 and 22 respectively. The signaling means 21 and 22 may be such as to give either audible or visible 90 signals or both, such as, for instance, whistles, bells or lamps or a combination thereof, but for the purposes of my invention, I shall hereinafter refer to signaling means 21 and 22 as white and blue lamps 95 respectively.

100 Since the signaling means 21 and 22 are controlled by the differential

action of the windings 10 and 11, either one or the other of the signaling means 21 and 22 will be operated on the occurrence of a ground on the system in accordance with 5 the voltages on the windings 10 and 11 coincident with such ground.

For showing the voltage on one of the windings and thus indicating the location and character of grounds on the system, 10 there is in shunt with the circuit 8 across the winding 11 an indicating means or voltmeter V. In order to facilitate the location of grounds, the voltmeter V may have, in addition to the usual graduations, markings such as A, B, C, D, E, etc., corresponding to various points at which grounds might occur.

For the purpose of illustration, the operation of my ground detector, as shown in Fig. 20 1, will be described on the basis of a practical example in which the direct electromotive force of each of the generators 3 is 600 volts and the counter electromotive force of each of the motors 6 is 900 volts. Grounds 25 will be assumed at different points A, B, C, D, and E on the system, the voltage drops across windings 10 and 11 and the operation of the signaling means 21 and 22 pointed out. The voltage drop across winding 11 30 is at all times indicated by the voltmeter V.

No ground on the system.

Assuming first normal conditions, that is no ground on the system, the voltage across 35 each of the windings 10 and 11 of control means 9 is the same and the voltmeter V will indicate 450 volts. The windings 10 and 11 will, therefore, be equally energized, holding the lever 17 in a balanced position and 40 neither of the circuit controlling members 12 and 13 will be moved to circuit closing position. Consequently, neither of the lamps 21, 22 will be lighted.

45 Ground at "A."

Assuming a good ground, that is one of practically no resistance, on the system at A, the voltage across winding 10 of control means 9 will be 300 volts and the voltage 50 across winding 11, indicated by the voltmeter V, will be 600 volts. Therefore, winding 11 will be more strongly energized than winding 10 and consequently will overcome the effect of winding 10 and move circuit 55 controlling member 13 to bridge contacts 20, thereby completing the circuit of signaling means or blue lamp 22 causing the same to be lighted.

60 Ground at "B."

With a good ground on the system, as at B, the voltage across winding 10 will be 900 65 volts and across winding 11 indicated by the voltmeter V, zero. Consequently, winding 10 will be energized and circuit controlling

member 13 moved to bridge contacts 19, thereby completing the circuit of signaling means or white lamp 21 and causing the same to be lighted.

70 Ground at "C."

With a good ground on the system, at C, the voltage across winding 11, indicated by the voltmeter V will be 900 volts and across winding 10, zero. Consequently winding 11 75 will be energized and circuit controlling member 13 moved to bridge contacts 20, thereby completing the circuit of signaling means or blue lamp 22 and causing the same to be lighted. 80

Ground at "D."

With a good ground on the system at D, the voltage across winding 11, indicated by the voltmeter V, will be 300 volts and across winding 10, 600 volts. Therefore, winding 10 will be more strongly energized than winding 11 and consequently will overcome the effect of winding 11 and move circuit controlling member 12 to bridge contacts 19, 90 thereby completing the circuit of signaling means or white lamp 21 causing the same to be lighted.

95 Ground at "E."

With a good ground on the system at E, the voltage across winding 11, indicated by the voltmeter V, will be 1200 volts and across winding 10, 300 volts. Therefore, winding 11 will be more strongly energized than winding 10 and consequently will overcome the effect of winding 10 and move circuit 100 controlling member 13 to bridge contacts 20, thereby completing the circuit of signaling means or blue lamp 22 causing the same to be 105 lighted.

Therefore, if there is a good ground on the system, it will be definitely indicated as at one of the three points A, C or E by the lighting of the blue lamp 22 or at one of the 110 two points B or D by the lighting of the white lamp 21 and for the particular one of the points A, B, C, D or E by the voltmeter reading corresponding to a good ground at that point. 115

For grounds in general, the following table shows the readings of the voltmeter V or voltages across winding 11, voltages across winding 10 and the indications of the signaling means 21 and 22 for a range from a ground of no resistance, that is a good ground, up to a ground of infinite resistance, that is no ground. This table or one of similar form may be furnished with equipments embodying my invention and the voltmeter V may be marked A, B, C, D, E, etc., at the voltages corresponding to good grounds at different points of the system. In this table, I have indicated voltage drops in one direction in each of the windings 10 and 11 as 120 125 130

positive and in the opposite direction as negative.

5	Voltages across—				Lamp lighted.	
	Voltmeter and winding 11.		Winding 10.			
	With ground resistance.					
10	Zero.	Infinite.	Zero.	Infinite.		
No.	600	450	-300	-450	None.	
A	600	450	-300	-450	Blue.	
B	0	450	-900	-450	White.	
C	900	450	0	-450	Blue.	
D	300	450	-600	-450	White.	
E	1,200	450	300	-450	Blue.	

It is obvious that the better the ground, that is the lower the resistance of the ground, 20 the more dangerous it will be to continue operation and therefore the more desirable it is to have a definite indication of the location and character of such a ground. As heretofore pointed out my invention gives a 25 definite indication on the occurrence of a good ground on the system.

It will also be evident from the preceding table that with the blue lamp lighted and the voltmeter reading substantially 900 30 volts, there may be a ground of appreciable resistance at E or a good ground at C. Likewise with the blue lamp lighted and the voltmeter reading substantially 600 volts, there may be a ground of appreciable 35 resistance at either C or E or a good ground at A. Similarly with the white lamp lighted and the voltmeter reading substantially 300 volts, there may be a ground of appreciable resistance at B or a good ground at D. With the white lamp lighted and the 40 voltmeter reading substantially zero, there is a good ground at B and with the blue lamp lighted and the voltmeter reading substantially 1200 volts, there is a good ground at E. If the voltmeter reads substantially 45 300, 600 or 900 volts, the operator is warned to look for a good ground at one of the points D, A or C, respectively, and although in the event of the 50 voltmeter reading 300, 600 or 900 volts, there may be a ground of appreciable resistance at the points B, C, or E, the operator knows nevertheless when and where to look for a good ground. It is also clear that the nearer 55 the voltmeter reads to 450 volts, the greater the resistance of the ground and with the blue lamp lighted a high resistance ground is indicated at A, C, or E and with the white lamp lighted at B or D.

60 In Fig. 2, I have shown a modification of my invention as applied to a plurality of dynamo-electric machines comprising generators 3 supplying motors 6 and connected alternately therewith in a series circuit. 65 In this modification of my invention, I pro-

vide in series with a circuit 8 across one of the dynamo-electric machines, for example, one of the motors 6, two preferably equal resistances 10" and 11". The circuit 8 is provided with a ground connection 14" intermediate the resistances 10" and 11" and in shunt with the circuit 8 across one of the resistances, for example, resistance 11", there is a voltmeter V for indicating the location and character of grounds on the system. The voltmeter V may have, in addition to the usual graduations, markings such as A, B, C, D, E, etc. to facilitate the location of grounds.

On the basis that the motors 6 and generators 3 rate the same electromotive forces assumed in connection with the description of the operation of the form of my invention shown in Fig. 1, it is obvious that the voltmeter V will indicate the same voltages as before for similar conditions and the voltages across resistances 10" and 11" will be the same as tabulated for windings 10 and 11 respectively of Fig. 1. Therefore, if voltmeter V indicates substantially 0, 300, 600, 900, or 1200 volts, the operator is warned to look for a good ground at one of the points B, D, A, C, or E respectively, although as heretofore explained, if the voltmeter reads substantially 300, 600 or 900 volts, there is not necessarily a good ground at D, 95 A, or C respectively. Also, as heretofore pointed out, if the voltmeter reading differs from 450 volts by a small amount, a ground of high resistance character is indicated at some one of the points A, B, C, D, or E.

In Fig. 3, I have shown a modification of my invention with the shunt circuit 8 connected across one of the motors 6 of a system comprising a plurality of motors and generators alternately connected in series as shown in Figs. 1 and 2. Electro-responsive means or relays 23 and 24 have their windings 10' and 11' connected in series with the shunt circuit 8 which is provided with a ground connection 14' intermediate the windings 10' and 11'. I may also include in series with the shunt circuit 8 and windings 10' and 11', if the latter are of relatively low resistance, resistances 25 and 26 which, if desired, may be made adjustable for varying the pick-up points of relays 23 and 24. If desired, however, the relays 23 and 24 may be provided with relatively high resistance windings and the resistances 25 and 26 omitted. Relay 23 operates to control the circuit of signaling means 21' by contact controlling member 12' which is arranged to bridge contacts 19' and relay 24 operates to control the circuit of signaling means 22" by contact controlling member 13' which is arranged to bridge contacts 20'. In shunt with the circuit 8 across the windings of one of the relays, for example winding 11' of relay 24 and its correspond-

125
130

ing resistance 26, there is a voltmeter V for indicating the location and character of grounds. The voltmeter V may have, in addition to the usual graduations, markings 5 A, B, C, D, E, etc. to facilitate the location of grounds.

In the modification of my invention shown in Fig. 3, and on the basis that the motors and generators of the system rate the electromotive forces heretofore assumed, the relays 23 and 24 are set to respond to a predetermined voltage between 450 and 600 volts. Referring to the voltages tabulated for windings 10 and 11 of Fig. 1, it will be 10 clear that under like conditions the same voltages will occur across winding 10' and resistance 25 and across winding 11' and resistance 26 respectively and therefore the voltmeter will indicate as heretofore explained. 15

It will be noted from the tabulated voltages that the pick-up points for relays 23 and 24 come within a voltage range, that is 450 to 600 volts, such that upon the occurrence of a ground on the system only one of the relays can respond at a time. Thus for a ground at A, C or E, relay 24 will operate to control the circuit of signaling means or blue lamp 22' and for a ground at B or D, relay 23 will operate to control the circuit of signaling means or white lamp 21'. It is also obvious from the tabulated voltages that, if the relays 23 and 24 are set to respond to voltages 20 somewhat greater than 450 volts, signaling means 22' will be operated by relay 24 upon the occurrence of either a low or high resistance ground at A, C or E and signaling means 21' will be operated by relay 23 upon the occurrence of either a low or high resistance ground at B or D, whereas if the relays 23 and 24 are set to respond to voltages somewhat less than 600 volts, signaling means 22' will be operated by relay 23 upon the occurrence of a good ground at A, C, or E or a ground of appreciable resistance at C or E and signaling means 21' will be operated by relay 24 upon the occurrence of a good ground at B or D or a ground of appreciable resistance at B. In any event, the operator is warned to look for a good ground at A, C, or E by the lighting of the blue lamp 22' or at B or D by the lighting of the white lamp 21' and the reading of the voltmeter V will indicate at which one of the points A, B, C, D, or E a good ground may be. 45

Although I have shown and described my invention in considerable detail, I do not wish to be limited to the specific details thereof, as shown and described, but may use such modifications, substitutions, or equivalents thereof, as are embraced within the scope of my invention. 60

65 What I claim as new and desire to se-

cure by Letters Patent of the United States, is:—

1. A ground detecting system comprising the combination with a plurality of sources of direct and counter electromotive forces alternately connected in a series circuit of a shunt circuit across one of said sources, means adapted to produce a voltage drop proportional to the current therethrough connected in series with said shunt circuit, a ground connection for said shunt circuit at an intermediate point in said voltage drop producing means, and means connected in circuit to measure the voltage drop between said intermediate point and one terminal of said shunt circuit. 70 75

2. A ground detecting system comprising the combination with an odd number of dynamo-electric machines consisting of motors and generators alternately arranged in a series circuit, of a shunt circuit across one of whichever of said machines occurs in an even number, signaling means, differential electro-responsive means in series with said shunt circuit connected to be controlled in response to the differences in potential between a ground on the system and the terminals of the machine across which said shunt circuit is connected to operate said signaling means, and means connected in circuit with said electro-responsive means for measuring one of said differences in potential. 80 85 90 95

3. A ground detector for an electric system wherein an odd number of sources of direct and counter electromotive forces are connected in a series circuit and wherein each of said direct electromotive forces has the same value and each of said counter electromotive forces has the same value, comprising a shunt circuit across one of whichever of said sources occurs in an even number, signaling means, a ground connection for said shunt circuit, means comprising two windings connected in series with said shunt circuit for controlling said signaling means in response to grounds on said system, and means for measuring the drop in voltage across one of said windings for grounds at different points of the system. 100 105 110 115

4. A ground detecting system comprising the combination with a plurality of dynamo-electric machines consisting of motors and generators alternately connected in a series circuit, said motors rating equal counter electromotive forces and said generators rating equal direct electromotive forces, of a shunt circuit across one of said dynamo-electric machines, electro-responsive means in series with said shunt circuit, a ground connection at an intermediate point in said electro-responsive means, signaling means adapted to be controlled by said electro-responsive means and means for measuring the difference in potential between said 120 125 130 135 140

- intermediate point and one terminal of said shunt circuit.
5. A ground detector comprising the combination with a plurality of sources of direct and counter electromotive forces connected alternately in a series circuit, of a circuit connected in shunt across the terminals of one of said sources and provided with a ground connection, signaling means, 10 electro-responsive means provided with two windings connected in series with said shunt circuit on opposite sides of said ground connection operative in response to the difference between the differences in potential 15 between said ground connection and said terminals to control said signaling means, and means connected in shunt with one of said windings for indicating the voltage thereon.
- 20 6. A ground detector comprising the combination with two motors and three generators alternately connected in a series circuit, each of said motors rating the same counter electromotive force and each of said 25 generators rating the same direct electromotive force, of a circuit connected in shunt with one of said motors, two windings connected in series in said shunt circuit, a ground connection for said shunt circuit 30 intermediate said windings, signaling means, and means acted upon by said windings operative in response to a difference in forces exerted by said windings to control said signaling means.
- 35 7. A ground detector comprising the combination with two motors and three generators alternately connected in a series circuit, each of said motors rating the same counter electromotive force and each of said 40 generators rating the same direct electromotive force, of a circuit connected in shunt with one of said motors, two windings connected in series in said shunt circuit, a
- ground connection for said shunt circuit intermediate said windings, signaling means, and means acted upon by said windings operative in response to a difference in forces exerted by said windings to control said signaling means, and means connected in circuit to measure the voltage drop 45 across one of said windings.
8. In a system of the class described wherein two motors each rating the same counter electromotive force are connected alternately in series with three generators 50 each rating the same direct electromotive force, a ground detector comprising a shunt circuit across one of said motors, a differential relay having two windings connected in series in said shunt circuit, a ground connection for said shunt circuit intermediate the windings of said relay, signaling means controlled by said relay, and a voltmeter connected in shunt with one of the windings of said relay.
9. In combination with an electric system wherein two motors each rating the same counter electromotive force are connected alternately in series with three generators each rating the same direct electromotive force, a ground detector comprising a shunt circuit across one of said motors, 55 signaling means, electro-responsive means comprising two windings connected in series in said shunt circuit operative in response to predetermined voltage conditions to control said signaling means, a ground connection for said shunt circuit intermediate said windings, and means for indicating the difference in potential between said ground connection and one of the terminals of said shunt circuit.

In witness whereof, I have hereunto set my hand this 19th day of April, 1921.

ALFRED C. FINNEY.
